UNITED STATES PATENT OFFICE

110,430

DESIGN FOR A COMBINATION MAIL BOX AND SUPPORT THEREFOR

Charles Geis, Cincinnati, Ohio

Application September 8, 1936, Serial No. 64,762

Term of patent 7 years

To all whom it may concern:

Be it known that I, Charles Geis, a citizen of the United States, residing at Cincinnati, in the county of Hamilton and State of Ohio, have invented a new, original, and ornamental Design for a Combination Mail Box and Support Therefor, of which the following is a specification, reference being had to the accompanying drawing, forming a part thereof.

In the drawing:

mail box and support therefor showing my new design;

Figure 2 is a front elevational view of the same, the supporting base shown in Figure 1 being omitted and the support being shown in a fragmentary condition for purposes of illustration.

I claim:

The ornamental design for a combination mail box and support therefor, as shown and described.

CHARLES GEIS.
